METHOD AND APPARATUS FOR MAKING
COILED WIRE MATERIAL IN ROPE FORMDaniel E. Hennessy, Leominster, Mass., assignor
to Springfield Wire & Tinsel Co., West Spring-
field, Mass., a corporation of Massachusetts

Application December 5, 1939, Serial No. 307,612

18 Claims. (Cl. 140—71)

In the making of air filters, sound absorbing devices, etc., it is desirable to have the previous wire product supplied in a self-supporting rope form which will not tangle with itself when wound up. In prior methods of making somewhat similar products it has been suggested that coiled metal strands be twisted together or laid side by side to form a rope, but insufficient bonding between the various strands is thus created and these strands may come loose from the surface of the rope with a consequent liability of tangling if the rope is packed in a container for shipment to the filter manufacturer.

It is one object of the present invention to produce a method and an apparatus in which coiled wire may be formed into a self-supporting continuous rope which will be substantially non-tangling, without the necessity of using an external binding wire. A further object is to produce a method and an apparatus of sufficient flexibility to permit the size and texture of the rope to be varied in order to suit special conditions. A further object is to provide improved mechanism for producing a hollow continuous tube of filtering material. A further object is to produce an improved method and apparatus by which the rope product may be formed and packed in a suitable container as a continuous operation. Additional objects will appear from the following description and claims.

Referring to the drawings:

Fig. 1 is a side elevation of one form of apparatus by which the present invention may be carried out;

Fig. 2 is an enlarged detail of a portion of the apparatus shown in Fig. 1;

Fig. 3 is a detail, on an enlarged scale, of a portion of the apparatus shown in Fig. 1;

Fig. 4 is a detail of a modified form of winding mandrel;

Fig. 5 is a detail of the coiled product both in its normal form and in the condition in which it is wound on the mandrel;

Fig. 6 is a diagram illustrating the manner of winding the rope product;

Fig. 7 is a detail section on line 7—7 of Fig. 1 taken on an enlarged scale;

Fig. 8 is an end view of the product obtained from the winding mandrel shown in Figs. 1 and 2;

Fig. 9 is an end view of the product obtained from the mandrel shown in Fig. 4;

Fig. 10 is a section on line 10—10 of Fig. 4;

Fig. 11 is a detail, similar to Fig. 4, showing a further modification of the winding apparatus for use when a hollow product is to be obtained;

Fig. 12 is a section on line 12—12 of Fig. 11 on a larger scale; and

Fig. 13 is an end view of the product made on the device of Fig. 11.

The rope-like product is formed by making a helically coiled strand of flat wire and cross winding this wire upon a rotating mandrel under a tension sufficient to keep the coils of the strand opened up, the wound portion of the coil being systematically advanced so that the windings progress longitudinally. Due to the fact that the coils are stretched out and to the fact that the strand is cross wound, the coils tend to interlock at the point of intersection of the strand. If the cross winding is given such a pitch that the strands extend roughly at an angle of 45° (although this may be varied greatly) a rope-like product of great stability will be produced. One specific form of apparatus will now be described in detail.

The initially coiled strand may be formed in any desired way, and while it may be formed by drawing a flat metal wire over a curling edge as described in the patent to Mason 2,121,527, dated June 21, 1938, it is preferably formed by winding on a small tapered needle or mandrel of either round or polygonal cross-section. In the form shown, the tapered mandrel 10 is held stationary in a frame 11 and a guide or frame 12 is mounted to rotate rapidly around it, drawing a flat wire 13 from a spool 14 which is permitted to rotate freely under a frictional drag. The frame may be rotated by a belt 15 extending from a motor 16 or other source of power. The mechanical construction of this winding mechanism is standard in the art of making tinsel or gimped material and need not be described in detail. A more complete description will be found in the Montgomery and Mason Patent 1,386,350, August 2, 1921.

The needle 10 is tapered and has a curved heel portion 17 so that the wire wound upon it is pushed off in the form of a continuous helix. Normally the spacing of the helix is fairly close, as is indicated on a greatly enlarged scale at 18 in Fig. 5, but as will be shown later the strand is drawn away from the mandrel by a windup mechanism operating at such a speed as to stretch the coils of the strand as shown at 19. To prevent this windup from drawing the coil completely off the mandrel, thereby preventing the formation of a helix, the strand may be passed around rolls 20 and 21 or the strand may be held against the mandrel by a pad or roller as indicated in the French patent to Martin 57,945, March 13, 1863.

The windup device shown in Figs. 1 and 2 is carried on a frame 22 clamped at 23 to an upright standard 24. A shaft 25 is rotatable in the frame 22 and carries a head 26. Extending downwardly from this head are spaced flat members 27 also appearing in Fig. 7. The outer surface of these members is made concave as at 28 to receive endless belts 29 which move downwardly along the outside of the members as indicated at 30 and return upwardly between the members. It will be apparent from Fig. 7 that the material wound around the flat mandrel thus formed will be in contact with the outer runs of the belts 29 but will be out of contact with the inner runs, and therefore the wound product will be caused to travel endwise at a rate dependent upon the speed of the belts.

At their lower ends the belts pass around guides or pulleys 31, a mere circular groove in the ends of the members 27 being generally sufficient, and at their upper ends pass around pulleys 32. Each pulley 32 has a worm wheel 33 affixed to it, both worm wheels engaging a common worm 34 on the lower end of a shaft 35 telescoping the shaft 25. The belts are additionally guided by idler pulleys 36 so that they will run in direct contact with the outer grooves in the bars 27.

The shaft 25 is driven by a chain connection 37 from an upright shaft 38 having a worm drive 40 from a countershaft 41 which may be driven from any desired source of power at a constant rate. The shaft 35 is driven by a chain connection 42 from the same shaft 38, the drives of the shafts 25 and 35 being slightly different so that the winding mandrel will be rotated at a constant rate and the belts will be fed continuously at a relatively slow rate. It will be understood that if both shafts were rotated at the same speeds no feeding would be accomplished, the drive of the belts being secured only by the differential speed. The feed could also be obtained by periodically holding the shaft 35 stationary, or by rotating it intermittently, but the constant drive described above is generally preferable as it gives a simple way of regulating the feed.

Intermediate the guide roll 21 and the wind-up is mounted a traverse mechanism best illustrated in Fig. 3. This comprises an arm 45 pivoted at 46 to a standard 47 and having at its ends one or more guide holes 48 for the strand. If a plurality of holes are used they are preferably spaced apart sufficiently to prevent the separate strands coming in contact with each other, as this would destroy the tightness of the interlock between the strands where they cross each other. Each guide hole is fed from a separate winding spindle, only one of which appears in Fig. 1. The arm 45 is oscillated periodically by a link 49 forked at 50 to embrace a shaft 51 and carrying a cam roll 52 engaging a cam 53 on the shaft. This cam is preferably of the uniform motion type, so as to minimize slowing down and dwell at the ends of the stroke, but a plain crank motion may be substituted with generally satisfactory results. The advantage of the uniform motion is that there is less tendency to form slack at the ends of the traverse. For the same reason, if a flat winding mandrel is used it is desirable to time the traverse with respect to the winding mandrel so that the flat mandrel will have its maximum drawing effect when the traverse is at the ends of its stroke. This effect is obtained when the flat

sides of the mandrel are at substantially right angles to the line of travel of the strand, and to preserve this timed relation the shaft 51 is driven by a chain drive 55 from a shaft 56 having worm drive and chain connections 57 and 58 with the shaft 41. If the additional refinement just referred to is not desired, the shaft 51 may be driven from any separate source of power or by a belt drive from shaft 41.

The wound strand 60 shown in Figs. 6 and 7 is stretched out as indicated at 19 in Fig. 5 and the helix has a substantial pitch as indicated in Fig. 6. This insures that the turns will interlock fully at their crossing points. Fig. 6 also shows by the arrows 61 and 62 the effect of systematically shifting the wound helices longitudinally of the mandrel, although this effect has been greatly exaggerated in the figure for clearness. It will be plain that by this means successive cross windings will overlap to form a continuous product having great stability along its length, this being adjustable by varying the angle of the helix.

The material is, as before stated, wound under tension and when it passes over the end of the mandrel it will contract as shown at 63 in Fig. 8, forming a compact cylindrical mass in which the wires are thoroughly interlocked.

In case a flatter product is desired the cylindrical rope of Fig. 8 may be passed between rollers, or the product may be treated during winding so that it will naturally assume a flattened form as indicated at 64 in Fig. 9. This may be done by any form of winding mechanism in which the flat wound mass is creased by causing it to slide along supports, one form being shown at Fig. 4. In this case the head 70 is rotated as before by a pulley 71 and bears a pair of threaded rods 72 connected by gearing 73 with a central shaft 74 driven as by a pulley 75. The rods 72 form a winding support and, due to the engagement of their threads with the inside of the wound mass, at once cause the latter to be fed off the end of the winding form and, by the sharpness with which the wire is bent coupled with the frictional rubbing contact of the screws, cause the edges of the wound mass to lose their tendency to return to circular form. While the product thus obtained will contract and interlock as shown at 64 it does not have the same tendency to assume a cylindrical form as that prepared with the use of belts. It is preferable to support the ends of the rods by a spacer 85 engaging reduced sections of the rods. This spacer is supported by a plate 86 attached to a U-shaped bracket 87 on the head 70. The plate 86 is preferably made wide enough so that it will guide the wound mass and prevent it from being dragged around the threaded rods.

The rope fed off the mandrel in either case is rotating on its axis, and to prevent kinking it is preferably received in a rotating container 88, which may be the one in which the rope is to be shipped. This container is received between guides 89 on a turntable 82 which may be driven from shaft 38 by a belt drive 83 suitably proportioned to the drive 37 to cause the rope to coil smoothly within the container.

In Figs. 11 and 12 is shown a modification adapted to produce a hollow tubular product, shown in end view at 90 in Fig. 13. For this purpose four screws 91 are shown, spaced around a circle as shown in Fig. 12 but driven from a common gear 92 as in the form of device shown in Fig. 4. To prevent the product being

creased around the screws a circular wooden or sheet metal frame 94 is secured as by struts 95 to the central plate 96. In this case interior tangling of the product is not desired, and to prevent this a roller 97 is carried by an arm 98 pivoted at 99 to any suitable place on the machine, and is pressed by a spring 100 against the wound product at a point below the lowermost point of reciprocation of the traverse 45. The condensation thus resulting will satisfy the interlocking tendency of the strands.

The described method is adaptable to widely differing conditions. Besides the obvious control by changing the size of the wire the size of the helical coils can be changed by using needles of different sizes, and by varying the tension under which the wire is wound on the needle. The size of these coils exerts a marked effect upon the texture of the ultimate product. This texture can also be varied by the tension under which the helical strand is wound and the pitch given to the helix.

The product formed in accordance with the method described will preserve its helical structure and will not "pack" undesirably on continued use even though it is made of relatively soft copper strand. This is due apparently to the interlocking of the coils by crossing rather than by laying them side by side. At the same time the product will preserve its rope-like form during shipment.

I claim:

1. A method of making air filtering or sound absorbing material which comprises forming a flat wire into a helical strand, cross-winding the strand under a tension sufficient to maintain its coils opened up, displacing at least some of the windings systematically in a longitudinal direction with respect to preceding underlying windings, and releasing the wound product progressively to permit it to contract into continuous rope form.

2. A method of making air filtering or sound absorbing material which comprises forming a flat wire into a helical strand, cross-winding the strand upon a form of flattened cross-section under a tension sufficient to keep its coils opened up, displacing at least some of the winding systematically in a longitudinal direction with respect to preceding underlying windings, relative to the form, ironing the inside edges of the wound product, and releasing the wound product progressively to permit it to contract into flattened, continuous rope form.

3. A method of making air filtering or sound absorbing material which comprises winding a flat wire into a strand having closely spaced helical coils, winding the strand upon itself in successively reversed long pitched helices, systematically displacing at least some of the windings in a longitudinal direction with respect to preceding underlying windings, maintaining the strand during winding under a tension sufficient to hold its normally closely spaced coils opened up, and releasing the wound product progressively to permit it to contract into continuous rope form.

4. A method of making air filtering or sound absorbing material which comprises forming a flat wire into a helical strand, and cross-winding the strand under a tension sufficient to maintain its coils opened up, displacing at least some of the windings systematically in a longitudinal direction with respect to preceding underlying windings.

5. A method of making air filtering or sound absorbing material which comprises forming a flat wire into a helical strand, cross-winding the strand under a tension sufficient to maintain its coils opened up, displacing at least some of the windings systematically in a longitudinal direction with respect to preceding underlying windings, condensing the wound material, and releasing the wound product progressively to permit it to contract into continuous rope form.

6. A method of making air filtering or sound absorbing material which comprises forming a flat wire into a helical strand, cross-winding the strand under a tension sufficient to maintain its coils opened up, displacing at least some of the windings systematically in a longitudinal direction with respect to preceding underlying windings, condensing the wound material, and releasing the wound product progressively to permit it to contract into continuous rope form, the diameter at which the product is wound being sufficiently great to prevent the center of the wound product from closing up when released.

7. A method of making air filtering or sound absorbing material which comprises forming a flat wire into a helical strand, cross-winding the strand under a tension sufficient to maintain its coils opened up, displacing at least some of the windings systematically in a longitudinal direction with respect to preceding underlying windings, and releasing the wound product progressively to permit it to contract into continuous rope form, the diameter at which the product is wound being sufficiently great to prevent the center of the wound product from closing up when released.

8. A machine for making air filtering or sound absorbing material in continuous rope form which comprises means for forming a continuous helix of flat wire, means for cross-winding the helix under tension sufficient to hold its coils opened up, and means to feed the wound material in a longitudinal direction during the winding operation.

9. A machine for making air filtering or sound absorbing material in rope form which comprises means for forming a continuous helix of flat wire, a rotating winding form having one free end, means for rotating the form at such a rate as to wind the helix under a tension sufficient to hold its coils opened up, and means to feed the wound material in a longitudinal direction along and off from the winding form during the winding operation.

10. A machine for making air filtering or sound absorbing material in rope form which comprises means for forming a continuous helix of flat wire, a winding form having one free end, means for rotating the form at such a rate as to wind the helix under a tension sufficient to hold its coils opened up, a guide for the helix located between the forming means and the winding form and reciprocable longitudinally with respect to the latter, and means for feeding the wound material progressively in a direction towards and off from the free end of the form.

11. A machine for making air filtering or sound absorbing material in rope form which comprises means for forming a continuous helix of flat wire, a rotating winding form having one free end, means for rotating the form at such a rate as to wind the helix under a tension sufficient to hold its coils opened up, a guide for the helix located between the forming means and the winding form and reciprocable longitudinally

with respect to the latter, a pair of oppositely positioned belts on the winding form each having one run in position to be engaged by the wound material, and means for driving the belts in a direction to feed the material towards and off from the free end of the form.

12. A machine for making air filtering or sound absorbing material in rope form which comprises means for forming a continuous helix of flat wire, a rotating winding form having one free end, means for rotating the form at such a rate as to wind the helix under a tension sufficient to hold its coils opened up, a guide for the helix located between the forming means and the winding form and reciprocable longitudinally with respect to the latter, a pair of oppositely positioned belts on the winding form each having one run in position to be engaged by the wound material, and means for driving the belts in a direction to feed the material towards and off from the free end of the form, said last-named means comprising pulleys carrying the belts, worm gears fixed to the pulleys, a common worm engaging the gears, and means for controlling the rotation of the worm with respect to the winding frame.

13. A machine for making air filtering or sound absorbing material in flat rope form which comprises means for forming a continuous helical strand of flat wire, a flat, rotating winding frame having a free end, means for rotating the frame at such a rate as to wind the strand under a tension sufficient to hold its coils opened up, a traverse mechanism for causing the strand to travel back and forth on the winding frame, and means for imparting a relative sliding movement to the wound strand and the winding frame at diametrically opposite points to displace the wound mass systematically towards the free end of the frame and to iron the inner surface of the wound mass whereby upon contraction it will assume a flattened form.

14. A machine for making air filtering or sound absorbing material in flat rope form which comprises means for forming a continuous helical strand of flat wire, a flat, rotating winding frame having a free end, means for rotating the frame at such a rate as to wind the strand under a tension sufficient to hold its coils opened up, a traverse mechanism for causing the strand to travel back and forth on the winding frame, and a pair of rotatable screw threaded rods carried by the winding frame and supporting the flat wound mass at diametrically opposite points to impart a relative sliding movement to the wound helix and the winding frame to displace the wound mass systematically towards the free end of the

frame and to iron the inner surface of the wound mass whereby upon contraction it will assume a flattened form.

15. A machine for making air filtering or sound absorbing material in rope form which comprises means for forming a continuous helix of flat wire, a rotating winding form having one free end, means for rotating the form at such a rate as to wind the helix under a tension sufficient to hold its coils opened up, means to traverse the material being wound to cause the turns to cross each other at a substantial angle, means to feed the wound material in a longitudinal direction along and off from the winding form during the winding operation, a container for receiving the product delivered from the mandrel, and means for rotating the container.

16. A machine for making air filtering or sound absorbing material in rope form which comprises means for forming a continuous helix of flat wire, a rotating winding form having one free end, means for rotating the form at such a rate as to wind the helix under a tension sufficient to hold its coils opened up, means for condensing the wound material on the winding form, and means to feed the wound material in a longitudinal direction along and off from the winding form during the winding operation.

17. A machine for making air filtering or sound absorbing material in rope form which comprises means for forming a continuous helix of flat wire, a rotating winding form having one free end, means for rotating the form at such a rate as to wind the helix under a tension sufficient to hold its coils opened up, means for condensing the wound material on the winding form, and means to feed the wound material in a longitudinal direction along and off from the winding form during the winding operation, the diameter of the winding form being sufficiently great to prevent the center of the wound product from closing up when released.

18. A machine for making air filtering or sound absorbing material in rope form which comprises means for forming a continuous helix of flat wire, a rotating winding form having one free end, means for rotating the form at such a rate as to wind the helix under a tension sufficient to hold its coils opened up, and means to feed the wound material in a longitudinal direction along and off from the winding form during the winding operation, the diameter of the winding form being sufficiently great to prevent the center of the wound product from closing up when released.

DANIEL E. HENNESSY.
